DESIGN FOR A TYPE CLEANING BRUSH

Robert B. Foster, Los Angeles, Calif., assignor to John B. Smiley, Los Angeles, Calif.

Application March 22, 1940, Serial No. 91,144

Term of patent 14 years

To all whom it may concern:

Be it known that I, Robert B. Foster, a citizen of the United States, residing at Los Angeles, in the county of Los Angeles, State of California, have invented a new, original, and ornamental Design for a Type Cleaning Brush, of which the following is a specification, reference being had to the accompanying drawing, forming part thereof, in which:

Fig. 1 is a front elevational view of a type cleaning brush showing my new design;

Fig. 2 is a side elevational view thereof; and,
Fig. 3 is a rear elevational view thereof.

I claim:

The ornamental design for a type cleaning brush, substantially as shown.

ROBERT B. FOSTER.
